UNITED STATES PATENT OFFICE.

ROBERT E. LEE, OF CINCINNATI, OHIO.

METALLIC WINDOW FRAME AND SASH.

Application filed July 6, 1925. Serial No. 41,840.

My invention relates to metallic window frames and sashes particularly adapted for use in windows having vertically slidable sashes.

5 The objects of my invention are to provide a simple, practical, economical and highly desirable window construction; to provide jamb cover pieces adapted to be conveniently connected with and removed 10 from the jambs of the frame; to provide means adapted to eliminate side or lateral movement of the sashes; and to provide means adapted to automatically close the openings between said jambs and said sashes 15 when said sashes are in closed position.

My invention consists in providing removable jamb cover pieces each having one side adapted to be secured in engagement with the respective jambs without the use 20 of screws, nails, rabbets or the like; in providing a sash rubbing plate adjustably fixed to each of the side rails of the upper and lower sashes and extending outwardly therefrom, whereby said plates are adapted to 25 engage the respective jamb cover pieces, thereby preventing lateral motion of the sashes; and in providing a closure block fixed to the outer side of each of said jamb cover pieces and adapted to closely seal the 30 upper and lower edges, respectively, of the lower and upper sashes and positioned opposite the meeting rails when said sashes are in closed position.

My invention also consists in the construction, combination, arrangement and location 25 of parts, as herein set forth and claimed.

In the drawings:

Fig. 1 is a broken perspective view of Fig. 4, taken on a plane corresponding to line 40 1-1 of Fig. 4;

Fig. 2 is a perspective view of the lower sash looking from the outside and showing the rubbing strips mounted thereon, and a portion of the window chains;

45 Fig. 3 is a fragmental perspective view of the upper and lower sashes in closed position showing their relation with the jamb closure block mounted on the parting strip;

Fig. 4 is an elevational perspective view 50 of the entire invention;

Fig. 5 is a transverse cross section taken on a plane corresponding to line 5-5 of Fig. 4;

55 Fig. 6 is a perspective view of one of the rubbing strips;

Fig. 7 is a perspective view of one of the jamb closure blocks;

Fig. 8 is a perspective view of the frame with the side supports or jambs broken away at X and X' to show their relation with the 60 parting strips, inside guides and sash mutton bars;

Fig. 9 is a perspective view of one of the inside sash guides partly broken off;

Fig. 10 is a perspective view of one of the 65 parting strips partly broken away; and

Fig. 11 is a perspective view of one of the jamb cover pieces partly broken away.

In the preferred construction of my invention I provide frame 1 comprising vertical 70 side supports or jambs 2 and 3 having head 4 and sill 5 suitably fixed thereto. The side jambs each have inwardly projecting pendulum strip 6 suitably fixed thereto for the purpose of preventing contact with each 75 other of the usual window weights suspended from chains 7 and 8, respectively, and supported by usual pulley (not shown) rotatably mounted in the usual manner and supported by the respective jambs. As clearly 80 shown in Fig. 5, jamb cover pieces 9 have U-shaped longitudinal edges 10 into which are received inwardly projecting edges or flanges 11 of the respective angular portions 12 of the jambs 2 and 3, respectively. The 85 other longitudinal edges or flanges 13, respectively, of jamb cover pieces 9 are fixed to the respective jambs by screws 14 combinedly received through the respective sash guides 15, inturned edges 16 of jambs 2 and 90 3 and longitudinal edges 13 of the jamb cover pieces, whereby the sash guides and the jamb cover pieces are securely retained in position.

Angular parting strips 17, respectively, 95 fitted into recesses 18, respectively, of jamb cover pieces 9 are retained in position by screws 19 combinedly received through the respective parting strips and the jamb cover pieces. Closure blocks 20, respectively, are 100 fixed to the central portion of vertical outer sides 21, respectively, of the parting strips 17 and are adapted to be closely engaged by the outer ends of meeting rails 22 and 23, respectively, of top 24 and bottom 25, respectively, of lower sash 26 and upper sash 27 whereby an air tight joint is formed between the sashes and the casing when the sashes are in closed position. When the lower sash is elevated and the upper sash is 110

lowered, meeting rails 22 and 23 have sufficient play relative to the sash guides to insure freedom of lowering and elevating the sashes, as by eliminating unnecessary friction between the parts, yet when the sashes are in closed position, the closure blocks provide an air tight connection between the sashes and the sash guides, thereby excluding undesirable elements such as wind, rain, 10 snow, dust, etc. from the building.

The closure blocks 20 preferably are constructed of bronze, for the reason that the sashes are usually constructed of steel, and as is well known, the frictional co-efficient of 15 steel and bronze is considerably less than the frictional coefficient of steel and steel, or other similar contacting metals, whereby the blocks will withstand considerable wear without the necessity of renewal.

20 For the purpose of preventing side or lateral play in the upper or lower sashes I provide adjustable bronze sash rubbing plates 28, clearly shown in Figs. 2, 5 and 6. As shown in Fig. 6, the rubbing plates have 25 spaced apart slots 29 therein. A rubbing plate is adjustably fixed to the top and bottom of side rails 30 and 31, respectively, of upper and lower sashes 27 and 26, by screws 32 received through slots 29 in the rubbing 30 plates and threaded at 33 to the vertical side rails, whereby outer ends 34 of the rubbing plates are adapted to engage the outer surface of the adjacent jamb cover pieces 9. When the rubbing plates are properly adjusted, by means of movement of the rubbing plates relative to screws 32, the side or lateral play of the sashes is reduced to a minimum, thereby providing a substantial and well fitted construction of the sashes 35 relative to the jamb cover pieces and parting strips. It is especially advantageous to reduce the side or lateral play of the sashes for the reason that rattling of the sashes is prevented, and also when the sashes are 40 manually elevated or lowered the possibility of the sashes becoming wedged in the frame is considerably reduced. Furthermore, by having slots 29 in the rubbing plates, after a considerable period of continuous use has 45 caused the plates to wear the jamb cover pieces, the plates may be readjusted relative to the jamb cover pieces, thereby providing means to obtain a tight fit between the sashes and the jamb cover pieces during 50 the entire life of the sashes and frame.

To install and assemble the invention, the pendulum strip 6 is secured in position in frame 1. The frame is then placed in the window opening in the wall, as shown in 55 Fig. 5 and suitably secured therein. The chains 7 and 8 having weights on one end are received over the pulleys (not shown) and the jamb covers 9 fixed in place. Then the upper sash 27 is inserted and two of the 60 chains are attached thereto. Next, place the

parting strips 17 in place and secure with screws 19. Then, attach the lower sash 26 to the remaining chains and insert the sash guides 15 which are held in place by screws 14. Should the occasion arise where access 70 to the pulleys or chains is desired, simply take the screws out of the sash guides and remove said guides. Then remove the chains from the lower sash allowing said sash to be removed. Then, take the screws out of the 75 parting strips and remove said strips. Then unhook the chains from the upper sash and remove said sash. Then remove the jamb cover pieces 9 whereby access to the pulleys and chains is permitted. To disassemble the 80 window reverse the operation. An advantage of having angular portions 12 integral with jambs 2 and 3, respectively, is that it makes a weather proof as well as burglar proof construction.

85 It is apparent that I have invented a simple, efficient and practical construction in metallic window frames and sashes whereby desirable and advantageous results are accomplished for the purposes intended.

90 While I have chosen to illustrate the form and construction of my invention by the accompanying drawings and explanations of the same, I desire to emphasize the fact that the form of construction and the explanation, as relates thereto, are not intended to include the various forms of modification in which my invention may be incorporated. It is understood that my invention resides 95 in the combination and arrangement of parts and in the details of construction, as herein claimed, and that changes in the precise embodiment of the invention, as herein disclosed, can be made within the scope of 100 what is claimed without departing from the 105 spirit of the invention.

110 What I claim as new and desire to secure by Letters Patent is:

1. In a metallic window construction having a frame and sashes, a jamb comprising a part of said frame and having on its outer side an inwardly turned flange positioned intermediate the sides of said jamb, an angular member on the outer side of said jamb having an inclined flange, a jamb cover piece having a hooked edge adapted to engage said inclined flange and adapted to be in fitted fixed relation with said angular number, an upper and a lower sash having side rails, a parting strip secured to said jamb cover piece, and a block fixed to the outer side of said parting strip and adapted to close the openings between said jamb and said sashes when said sashes are in closed position.

115 2. In a metallic window construction having a frame and sashes, a jamb comprising a part of said frame and having on its inner side an inwardly turned flange positioned intermediate the sides of said jamb, a jamb 120

cover piece adapted to engage said inwardly turned flange and adapted to be fixed in this position, an upper and a lower sash having side rails, a parting strip secured to said 5 jamb cover piece, a block fixed to the outer side of said parting strip and adapted to close the openings between said jamb and said sashes when said sashes are in closed position, a rubbing plate having a slot there- 10 in and fixed to one of said side rails and having its outer edge adapted to engage said jamb cover piece, whereby the lateral motion of said sashes is minimized.

3. In a metallic window construction having a frame and sashes, a jamb comprising a part of said frame and having an inclined flange positioned intermediate the sides of said jamb, a jamb cover piece having a hooked edge adapted to engage said inclined 20 flange and adapted to be fixed in this position, an upper and a lower sash having side rails, a parting strip secured to said jamb cover piece, a block fixed to the outer side of said parting strip and adapted to close the 25 openings between said jamb and said sashes when said sashes are in closed position, a rubbing plate fixed to one of said side rails and having its outer edge adapted to engage said jamb cover piece, whereby the lateral motion of said sashes is minimized.

4. In a window, a frame, upper and lower sashes, a jamb comprising a part of said frame and having an inwardly turned edge, a jamb cover piece having a hooked edge 35 adapted to engage said inwardly turned edge, a parting strip secured to said jamb cover piece, and a block fixed to the outer side of said parting strip and adapted to close the opening between the meeting rails of said sashes and said parting strip when said sashes are in closed position.

5. In a window, a frame, upper and lower sashes, a jamb comprising a part of said frame and having an inwardly turned edge, a jamb cover piece having a hooked edge 45 adapted to engage said inwardly turned edge, a parting strip secured to said jamb cover piece, a block fixed to the outer side of said parting strip and adapted to close the openings between the meeting rails of said sashes and said parting strip when said sashes are in closed position, and a rubbing plate having a slot therein and fixed to one of said side rails and having its outer edge 55 adapted to engage said jamb cover piece whereby the lateral motion of said sashes is minimized.

6. In a window, a frame, upper and lower sashes, a jamb comprising a part of said frame and having an inwardly turned edge, a jamb cover piece having a hooked edge 60 adapted to engage said inwardly turned edge, a parting strip secured to said jamb cover piece, a block fixed to the outer side 65 of said parting strip and adapted to close

the openings between the meeting rails of said sashes and said parting strip when said sashes are in closed position, and a rubbing plate fixed to one of said side rails and having its outer edge adapted to engage said 70 jamb cover piece whereby the lateral motion of said sashes is minimized.

7. In a window, a frame, upper and lower sashes and each having side rails and meeting rails, a jamb comprising a part of said 75 frame and having a longitudinal edge, a jamb cover piece having a hooked portion adapted to engage said longitudinal edge, a parting strip secured to said jamb cover piece, a block fixed to the outer side of said 80 parting strip and adapted to close the opening between said meeting rails and said jamb when said sashes are in closed position and means for securing said jamb cover piece in fixed relation to said jamb. 85

8. A window comprising a frame and an upper and a lower sash having side rails and meeting rails, a jamb comprising a part of said frame, a jamb cover piece fixed to said jamb, a parting strip secured to said jamb 90 cover piece, a block fixed to the outer side of said parting strip and adapted to close the openings between said jamb and said meeting rails when said sashes are in closed position. 95

9. A window comprising a frame and an upper and a lower sash having side rails and meeting rails, and a separate bronze rubbing plate having a slot therein and adjustably fixed to one of said side rails through said slot and having its outer edge adapted to engage said frame, whereby the lateral movement of said sashes is minimized. 100

10. A window comprising a frame and an upper and a lower sash and each of said sashes having side rails and meeting rails, a pair of jambs comprising a part of said frame, a jamb cover piece fixed to each of said jambs, a parting strip secured to each of said jamb cover pieces, a bronze block 110 fixed to the outer side of each of said parting strips and adapted to close the openings between said jambs and said meeting rails when said sashes are in closed position, and a bronze rubbing plate adjustably fixed to the upper and lower edges of each of said side rails and having their outer edges 115 adapted to engage said jamb cover pieces, respectively, whereby the lateral motion of said sashes is minimized. 120

11. A window comprising a frame and an upper and a lower sash and each of said sashes having side rails and meeting rails, a pair of jambs comprising a part of said frame, a jamb cover piece fixed to each of said jambs, a parting strip secured to each of said jamb cover pieces, a block fixed to the outer side of each of said parting strips and adapted to close the openings between said jambs and said meeting rails when said 125 130

sashes are in closed position, and a rubbing plate adjustably fixed to the upper and lower edges of each of said side rails and having their outer edges adapted to engage said jamb cover pieces, respectively whereby the lateral motion of said sashes is minimized.

12. A window construction comprising a frame having spaced apart jambs, an upper and lower sash having side rails and meeting

rails and a plurality of rubbing plates each having spaced apart parallel slots therein, a screw extending through each slot into said side rails, respectively, whereby said plates may be detachably mounted and adjustably secured in any desired position relative to said sashes and jambs, respectively, whereby the lateral movement of said sashes is minimized. 15

ROBERT E. LEE.
